ROLLING TOY

Joseph Davis, Arlington, N. J., assignor to Joseph Davis Plastics Co., Arlington, N. J., a corporation of New Jersey

Application January 15, 1948, Serial No. 2,501

4 Claims. (Cl. 46—49)

1

This invention relates to improvements in toys, particularly to rolling toys. It is the object of this invention to provide a rolling toy having novel structural features whereby, when the toy is rolled, unique optical effects are obtained.

These and other advantageous objects, which will appear from the drawings, and from the description hereinafter, are accomplished by the structure of my invention, of which embodiments are illustrated in the drawings. It will be apparent, from a consideration of said drawings, and the following description, that the invention may be embodied in other forms suggested thereby, and such other forms as come within the scope of the appended claims are to be considered within the scope and purview of the instant invention.

In the drawings:

Fig. 1 is an exploded view of a rolling toy embodying the invention, in exploded or disassembled condition,

Fig. 2 is a side elevational view of the assembled rolling toy,

Fig. 3 is an end elevational view thereof, taken on line 3—3 of Fig. 2, and

Fig. 4 is a schematic view illustrating the movement of the parts in the operation of the toy.

As shown in the drawings, the toy comprises a rotor 10 provided with medial vanes 12, 12' and having tapered ends 13, 13'. The rotor is positioned interiorly of a transparent roll shell 14, the latter having convex ends 15, 15', internally concave. If desired, the shell 14 may be formed of the halves 16, 16' which may be secured together by cementing or other suitable means and which may be of any desired or convenient outline. For example, the said shell may be made in the form of a cylinder or other form having convex ends. The rotor is of a lesser length than the greatest length of the shell member interiorly. The greatest length of the shell member occurs longitudinally medially thereof and is indicated by the line 20. As the rotor 10 is of less length than the medial longitudinal line 20 of the shell interiorly thereof, and the ends 15, 15' of the shell 14 are internally concave, the said rotor will normally rest at a plane below the horizontal longitudinal medial or center line 21 of said shell. As the ends 13, 13' of the rotor are tapered and terminate in an extremely small diameter, the said rotor will rotate, when the toy is rolled, at a much higher rate than the roll toy. Thus, for each single revolution of the roll toy, the number of revolutions of the rotor will be a very high multiple of one. The shell 14 is made of a transparent or

2

translucent material so that the rotor may be viewed therethrough; the vanes 12, 12' of the latter are preferably colored, and may be contrastingly colored, so that the optical effect obtained upon the rolling of the toy is unique and has considerable eye-appeal.

As the ends 15, 15' of the roll shell 14 are internally concave, the rotor apparently tends, when the roll toy has been brought to a stop after rotating, to rotate in an arc and then to settle in the crest of the arc. This is schematically illustrated in Fig. 4. The line 21 is a circumference line within an end 15 or 15' on which the rotor end normally rests, in the rotation of the shell 14. When the shell 14 is rotated and brought to rest, the rotor appears to rotate within an arc 22, and, depending on the previous rate of rotation of the shell, etc., may have reciprocating rotation in said arc more than once, finally settling in the apex of said arc, which apex point would correspond to the circumference line 21. It will be understood that the arc 22 of rotation of the rotor is repeated circumferentially within the convex ends equidistant from the medial line 20 to infinity. Three of such arcs are indicated in dot-dash lines in Fig. 4. The rotor may be provided with guard discs 18, 18' secured thereto adjacent the tapered ends thereof, which, with the medial vanes 12, 12', stabilize the rotor and prevent accidental displacement thereof. The shell 14 may be provided with rails 17, 17' of greater diameter than the shell so that the toy will roll on said rails, if so desired.

Beads 19 may be positioned within the roll shell 35 to add a sound effect to the toy when rolled.

It is found that the toy above described presents unique optical effects in operation; the rotor appears to be well balanced by the provision of the medial vanes 12, 12' and guard discs 18, 18'. It is found that the rotor rotates at a high rate of speed and in a smooth fashion pursuant to the invention above described.

The parts may be made of any suitable material it being found convenient to make the same (or 45 at least the shell 14) of plastic materials, for which purpose the shell 14 may be made of halves 16, 16' which are mirror-images of each other. As above mentioned, the roll shell 14 may be formed as a cylinder or have any other medial section desired; the toy will operate just as efficiently, as long as the ends 15, 15' secured to the medial portion of the roll shell are convex. The material of which the roll shell is made is preferably a transparent or translucent material so 50 that the rotor may be clearly viewed therethrough.

The medial vanes 12, 12' are secured to the rotor 10 so as to lie in substantially the same general plane and are preferably mirror images of each other so as to balance the rotor. They may be made of any desired or convenient outline, and in any desired or convenient color. The word "color" is used above and in the claims to denote, and is defined to mean, anything other than a transparency. Thus, if vanes of natural or artificial black, white, brown or other color or translucency, are provided, visible as such through the transparent shell body, they would come within the definition of "colored" as used herein and above noted.

Having thus described my invention what I claim as new and desire to secure by Letters Patent is:

1. A roll toy comprising a closed hollow transparent shell body having oppositely disposed internally concave ends therein, a longitudinally and axially balanced rotor having ends of relatively small diameter, said rotor being of substantially less mass than the shell body, and of less length than the maximum axis line between said oppositely disposed concave ends so as to have its small diameter ends rest within and freely roll on said oppositely disposed concave ends below said maximum axis line, the maximum radius of said rotor at any point between its ends being less than the distance from its axis to the shell body at that point so as to permit the rotor to freely rotate, said rotor including colored vanes secured thereto and visible through the transparent shell body, said shell body including means upon which it can roll about said maximum axis line whereby said shell body may be rolled to cause visible rotation of the rotor at a greater rate of rotation than said shell body.

2. A roll toy comprising a closed hollow transparent shell body having oppositely disposed internally concave ends therein, a longitudinally and axially balanced rotor having ends of relatively small diameter, said rotor being of substantially less mass than the shell body, said rotor being of less length than the maximum axis line between said oppositely disposed concave ends so as to have its small diameter ends rest within and freely roll on said oppositely disposed concave ends below said maximum axis line, said rotor including colored vanes secured thereto and visible through the transparent shell body, and a pair of encircling parallel rail members secured exteriorly of said shell body at right angles to said maximum axis line, the cylinder defined by the peripheries of said rail members entirely en-

closing said shell body, whereby said shell body may be rolled on said rail members to cause visible rotation of the rotor at a greater rate of rotation than the shell body.

3. A roll toy comprising a closed hollow transparent ellipsoid shell body having internally concave ends therein, a longitudinally and axially balanced rotor having ends of relatively small diameter, said rotor being of substantially less mass than the shell body, said rotor being of less length than the major axis line of said ellipsoid shell body so as to have its small diameter ends rest within and freely roll on said concave ends below said major axis line, the maximum radius of said rotor at any point between its ends being less than the distance from its axis to the shell body at that point, said rotor including multi-colored vanes secured thereto and visible through the transparent shell body, whereby said shell body may be rolled about the major axis to cause visible rotation of the rotor at a greater rate of rotation than said shell body.

4. A roll toy comprising a closed hollow transparent ellipsoid shell body having internally concave ends therein, a longitudinally and axially balanced rotor having its ends of relatively small diameter, said rotor being of substantially less mass than the shell body, said rotor being of less length than the major axis line of said ellipsoid shell body so as to have its small diameter ends rest within and freely roll on said concave ends below said major axis line, the maximum radius of said rotor at any point between its ends being less than the distance from its axis to the shell body at that point, said rotor including colored vanes secured thereto and visible through the transparent shell, and a pair of encircling parallel rail members secured exteriorly of said ellipsoid shell body at right angles to its major axis, the diameter of said rail members being greater than the minor axis of said ellipsoid body, whereby the shell body may be rolled on said rail members to cause visible rotation of the rotor at a greater rate of rotation than said shell body.
